UNITED STATES PATENT OFFICE.

EWALD GOLTSTEIN, OF BONN, AND EBERHARD MEYER, OF TROISDORF, GERMANY.

CLOSURE FOR BOTTLES AND LIKE RECEPTACLES.

Application filed April 22, 1927, Serial No. 185,856, and in Germany May 1, 1926.

This invention relates to closures for bottles or like receptacles of the kind having a packing disc covered with an insoluble cuticle placed inside a metal capsule.

5 The object of the invention is to provide a closure for bottles which will be absolutely tight.

Another object of the invention is to form a closure which will be impervious to liquids and will not impart a taste thereto or be acted upon thereby.

The present invention consists in the improved bottle closure to be hereinafter described and more particularly pointed out 15 in the claims.

The invention is clearly illustrated in the accompanying drawings, in which:—

Fig. 1 is a perspective view showing a 20 combination of the cuticle with cellulose cardboard,

Fig. 2 is an elevational detail of a slightly modified form of the invention, and

Fig. 3 is a vertical sectional view embodying the combination of a metal capsule 25 and pad.

According to the present invention, each bottle closure is formed of a metal capsule which is fitted with a packing disc, composed of textile material or of paper, cardboard or like fibrous material and covered 30 on one or both sides with an elastic cuticle.

By this means the bottle is hermetically sealed and the liquid comes in contact only with the glass and the cuticle. The cuticle 35 must be so flexible and elastic that it will perfectly adapt itself to the shape of the edge of the bottle mouth and for this purpose it is formed of nitrocellulose or its solution in volatile organic solvents. The 40 flexibility of the nitrocellulose may be if required enhanced by the addition of a gelatinizing agent.

The following may be taken as typical examples of suitable gelatinizing agents:—

- 45 (1) Triacetic-ester of glycerine.
- (2) Tricresyl-ester of phosphoric acid.
- (3) Ethyl ester of phthalic acid.

By coating with such solutions extremely tough cuticles are formed on pads made of 50 textile materials or made of paper, cardboard or like fibrous materials, which will provide an excellent packing material.

The solution, when applied, penetrates the surface layer of the cardboard as if with 55 small roots, and, after being dried, forms

a cuticle which is so intimately combined with the surface layer of the cardboard that, when forcibly removed, parts of the cardboard are torn away with it.

In Figure 1 of the accompanying drawings, this combination of the cuticle with cellulose cardboard is shown. If the manufacture of the separate small discs from sheets of the material keeps pace with that of the capsules they may retain the form 60 of a flat disc. If, however, they are made separately, it is necessary, in order that they may lie correctly in the capsules, either to coat them on both sides of the cuticle or to give them a certain curvature, as shown in 65 Figure 2. This curvature makes it possible to introduce the discs correctly into the capsules by means of sorting machines.

In Fig. 3 there is shown another form of the invention and in reducing this feature 75 of the invention to practice each bottle 1 is provided with a closure generally indicated by the numeral 2 comprising a metal capsule 3 which is fitted with a packing disc 4 composed of textile material of paper, cardboard or like fibrous material and covered 80 on both sides with an elastic cuticle 5.

Having now described our invention, what we claim as new and desire to secure by Letters Patent is:—

1. A closure for bottles and like receptacles, comprising a metal capsule, a pad of artificially manufactured fibrous material inserted in said capsule, and an elastic cuticle composed of nitrocellulose attached to 90 said pad.

2. A closure for bottles and like receptacles, comprising a metal capsule, a pad of artificially manufactured fibrous material inserted in said capsule, and an elastic cuticle composed of nitrocellulose treated with 95 a gelatinizing agent attached to said pad.

3. Packing material for bottle closures and the like, comprising a pad of artificially manufactured fibrous material coated with 100 an elastic cuticle composed of nitrocellulose.

4. Packing material for bottle closures and the like, comprising a pad of artificially manufactured fibrous material coated with an elastic cuticle composed of nitrocellulose treated with a gelatinizing agent.

In testimony whereof we affix our signatures.

EWALD GOLTSTEIN.
EBERHARD MEYER.
